UNITED STATES PATENT OFFICE.

RICHARD H. STRATTON, OF GIANT, CALIFORNIA, ASSIGNOR TO ATLAS POWDER COMPANY, OF WILMINGTON, DELAWARE, A CORPORATION OF DELAWARE.

MACHINE FOR FORMING HOLES IN DYNAMITE CARTRIDGES.

Application filed March 18, 1925. Serial No. 16,269.

To all whom it may concern:

Be it known that RICHARD H. STRATTON, a citizen of the United States, residing at Giant, in the county of Contra Costa and State of California, has invented certain new and useful Improvements in Machines for Forming Holes in Dynamite Cartridges, of which the following is a specification.

This invention relates to a machine for forming holes in dynamite cartridges for the reception of the exploders. In tunnel blasting "delay action" exploders are employed. These range from a "no delay" which measures about 3 inches long to a No. 8 delay which is 10^{1/16} inches long. In order that these delay exploders may be properly inserted in the particular dynamite cartridge which is to constitute the priming cartridge of a charge, which may consist of quite a number of sticks of dynamite, it is necessary to form a hole in the gelatine of the cartridge. Heretofore this has been accomplished by thrusting a tapered stick into the priming cartridge by hand. Under this crude method it is exceedingly difficult to keep the hole centrally located with respect to the cartridge. If the hole is not centrally located with respect to the cartridge and the exploder gets too near the side walls of the cartridge there is grave danger of a premature explosion, either during the time that the cartridge is being placed in the bore hole or during the ramming of the cartridge after being placed in the bore hole.

The primary object of the present invention is, therefore, to provide a machine constructed of non-sparking material throughout and arranged to form the necessary holes in the priming dynamite cartridges, said machine being so constructed and arranged that the operator may perform the work indicated, with a minimum of fatigue and with a maximum of safety and efficiency.

In the accompanying drawings, wherein like characters of reference designate corresponding parts throughout the several figures,

Figure 1 is a side elevation of the machine constructed in accordance with the invention,

Figure 2 is a plan view of said machine, Figure 3 is an end elevation of the machine,

Figure 4 is a transverse sectional view on line 4—4 of Figure 1.

Figure 5 is a perspective view of the 55 shuttle,

Figure 6 is a transverse section through the shuttle,

Figure 7 is a sectional view of the head of the spiral,

Figure 8 is a sectional view through the bearing block of the spiral.

In the drawings, 5 designates a horizontal table which constitutes a support for a wooden shuttle 6, having a concave seat in its upper face that is adapted to receive the cartridge to be punched. The opposite ends of this concave seat are closed by sheets of fibre 7 and 8 which properly position the stick of dynamite and prevent it from shifting endwise during the penetration of the punch and during the withdrawal of said punch. An operator's seat 9, that is supported upon legs 10 and 11, is disposed at that end of the table which carries the shuttle 6, and in such position that an operator seated thereon may grasp a handle 12 and through the medium of a link 13 swing a lever 14 upon the pivot 15. This pivot is carried by the outer ends of links 16 and these links, are in turn, pivoted at 17 to a fulcrum bolt 18, the shank of which is engaged by a nut 19. Braces 20 and 21 impart the necessary rigidity and strength to the structure. The lever 14 comprises a yoke 22 intermediate its ends and the sides of this yoke are engaged by pins 23 of a split ring 24 which is mounted in a grooved head 25 of a spirally grooved bar 26. This bar is mounted for reciprocation and rotation through a brass block 27 that is mounted upon the table 5. The spiral bar, hereinafter referred to as the spiral, is preferably made of bronze and carries a tapered bronze punch 28. When the spiral and punch are drawn toward the shuttle by the 95 operation of the handle 12 and lever 14 rotation is imparted to the spiral and punch due to the engagement, in the spiral groove, of a brass pin 29 that is carried by the brass block 27. In addition this pin serves as a 100 stop to limit the movement of the punch and to determine the extent to which the punch may enter the stick of dynamite. Openings 30, formed in the bottom of the shuttle, per-

mit the passage of the "sawdust" from the dynamite cartridge to be discharged through corresponding openings 31 of the table, so that after a cartridge has been punched the 5 shuttle may be rendered perfectly clean and free of any residual dynamite, the presence of which might, otherwise, tend to destroy the centered relation of dynamite and punch. To facilitate the action of the mechanism 10 and to help support the weight of the levers, a spring 32 is connected at 33 to the table and at its opposite end to the pivot 15. The machine herein shown and described is constructed in such a manner that the 15 work of punching the cartridges may be performed with great speed and with a minimum of trouble upon the part of the operator. In use the operator seats himself at the rear of the machine with a box of cartridges on one side and an empty box on the other. He places a cartridge in the shuttle and by means of the handle pulls the punch toward him, thus causing the punch to revolve. The operator continues to pull until 20 further motion is prevented by the stop, at which point the punch has penetrated the cartridge to the required depth. The punched cartridge is then placed in the empty box and the sawdust brushed through 25 the holes. A new cartridge is then placed in the shuttle and the operation repeated.

In some of the machines heretofore proposed for this purpose it was necessary for the operator to place the cartridge in a vertical shuttle and to hold said shuttle closed with one hand while operating the punch with the other. This placed the operator in a very awkward position and he was unable to apply his strength to the best advantage. Furthermore, it was difficult to withdraw the punch and no provision was made to remove the sawdust from the shuttle, with the result that the presence of this sawdust 40 frequently destroyed the alignment of the cartridge and punch.

It is to be understood that the invention is not limited to the precise construction set forth, but that it includes within its purview whatever changes fairly come within 45 either the terms or the spirit of the appended claims.

Having described my invention what I claim is:

1. In a machine of the character described the combination with a seat for a dynamite cartridge, disposed in a substantially horizontal plane so that a cartridge may rest therein by gravity, of a punch movable in a horizontal plane adapted to pierce a cartridge disposed in said seat. 55

2. In a machine of the character described the combination with a seat for a dynamite cartridge, disposed in a substantially horizontal plane so that a cartridge may rest therein by gravity, of a rotative punch movable in a horizontal plane adapted to pierce a cartridge disposed in said seat. 60

3. A machine of the character described comprising a supporting table having an operator's seat at one end, a horizontally reciprocating punch at the opposite end, and a concave seat for a dynamite cartridge between the punch and operator's seat, in combination with manually operable means by which the operator may reciprocate the 70 punch toward and from him. 75

4. A machine of the character described comprising a supporting frame work, an operator's seat at one end thereof, a horizontally movable punch and spiral at the opposite end thereof, a concave seat for a dynamite cartridge between the punch and the operator's seat, and manually operable levers by which an operator seated upon 80 said seat may reciprocate the spiral and 85 punch toward and from him.

5. A machine of the character described comprising a supporting frame work, an operator's seat at one end thereof, a guide block at the opposite end thereof, a spirally 90 grooved bar movable in the guide block, means carried by the guide block and engaging the groove of the spiral to cause rotation of the same when the grooved bar is moved longitudinally with respect to the 95 guide block, an operating handle, a lever comprising a yoke, to which said handle is connected, and connections between said yoke and the spirally grooved bar.

In testimony whereof he affixes his signature.

RICHARD H. STRATTON.
